UNITED STATES PATENT OFFICE.

THOMAS GEORGE STILES, OF ARLINGTON, NEW JERSEY.

COMBINED CONTROLLER AND SWITCH LOCK

1,405,693.

Specification of Letters Patent

Patented Feb. 7, 1922

Application filed July 19, 1917. Serial No. 181,572

To all whom it may concern:

Be it known to any concern:
5 Be it known that I, THOMAS GEORGE STILES, a citizen of the United States, and resident of Arlington, in the county of Hudson and State of New Jersey, have invented certain new and useful Combined Controllers and Switch Locks, of which the following is a specification.

This invention relates to selective control-
ling means, and more particularly to selec-
tive controlling means for railway switch-
ing and signal apparatus.

15 and signal apparatus.

A primary object of the invention resides in the provision of means, preferably positively-actuated, which will properly control the signal circuits when the switch is in its various positions.

With this and other objects in view, such as will appear as the description progresses, the invention comprises the combination and arrangement of parts as set forth in and falling within the scope of the appended claims.

Referring to the drawings:—

25 Fig. 1 is a diagrammatic view of a specific application of the invention showing the same associated with the usual signal circuits;

Fig. 2 is a plan view of the main switch apparatus;

Fig. 3 is a side elevation, partly in section, of the same, the section being taken on line 3-3 of Fig. 2;

Fig. 4 is an enlarged plan view of that portion of the apparatus which includes the plunger lock;

Fig. 5 is a sectional view taken on line 5-5 of Fig. 4 showing the plunger lock in its operative or locking position;

40 Fig. 6 is an elevational view of one of the cams used in operating the switch mechanism;

Fig. 7 is a view, taken at right angles to Fig. 6, of the same cam; Figs. 8 and 9 are elevational views of the

Fig. 10 is a fragmental plan view of a

Fig. 10 is a fragmental plan view of a modified form of the switch mechanism; and

50 11—11 of Fig. 10. The drawing is the section in a

These drawings, in the first nine figures thereof, illustrate one use of the selective controlling apparatus, but other uses of the

specific apparatus can be made to take care of various phases of interlocking and signaling conditions. 55

The invention, in the application or use of the same here shown, includes a polarized relay which is capable of operating the proper signal circuit only when the railway switch is closed, and consists further of a pole changer for the relay operated by the switch, and a plunger lock for the switch which operates in conjunction with means for short-circuiting the relay, so that the latter will be de-energized when the switch is unlocked. 60 65

Referring first to the diagram illustrated in Fig. 1, the railway switch points are indicated by the reference character S, which points are adapted to be shifted to either of their positions, that is to say, to open the main line or the side track by suitable means, here shown as a rod A, which extends to the tower. Extending between the switch points S is a cross bar B, from which a lock rod C extends. With this lock rod, a plunger lock D co-operates and is adapted to be shifted manually to engage the lock rod to maintain the switch in either of its operative positions. A rod E extends from the bar B and is connected to and operates a pole changer F for the polarized relay G. This pole changer F consists, broadly, of a pair of movable switch blades 1 and 2, which are adapted to engage contacts 3, 4 and 5. Extending from the contact 3 is a conductor 6, which is connected to the winding of the magnet G, while extending from

the other end of the winding is a conductor 90
7 which is connected to the contact 4. A
conductor 8 extends from the contact 5 and
is joined to the conductor 6 at 9. From
the stationary end of the switch blade 1, a
conductor 10 extends, the other end of which 95
terminates in a contact point 11, and in
which conductor a battery 12 is interpolated.
A conductor 13 extends from the stationary
end of the blade 2 and is connected to a
movable switch blade 14 which is operated 100
by the plunger lock D, being connected
thereto in a manner which will later ap-
pear in the description of the particular
apparatus used. A conductor 15 is con-
nected at 16 to the conductor 6 and to a 105
switch blade 17, which is operated by the

plunger lock D and is adapted to engage the terminal 18, which is carried by a conductor 19, the latter being joined at 20 to the conductor 7.

5 Thus, when the switch points S are shifted into the position illustrated in Fig. 1, for instance, a circuit will be completed through the magnet G, provided the plunger lock D is in its operative or locking position. This 10 circuit will start from the battery 12, through the conductor 10, the switch blade 1, the contact 3, the conductor 6, the winding of the magnet G, the conductor 7, the contact 4, the switch blade 2, the conductor 13, the 15 switch blade 14, the contact 11, back to the battery through the conductor 10. It will, of course, be understood that in the drawings, the plunger lock is in its inoperative position, but when it is in its operative position, the switch blade 14 will engage the contact 11, and the circuit just described will be completed. This completion of the 20 circuit will energize the magnet G and will attract a switch blade 21, which is part of an ordinary double polarized relay used in connection with the usual or ordinary form of signal apparatus. The attraction of this blade will close the switch so that a circuit will be established from a battery or other 25 suitable source of electrical energy 22, through a conductor 23, through the operating mechanism of a signal H, through a conductor 24, through a switch 25 which closes concurrently with the switch 21, through a conductor 26, through the switch 21, and a conductor 27, when manually operable switch 28, in the latter conductor, has been closed. When, however, the switch points 30 S are shifted to their opposite position and locked in such position, the switch blades 1 and 2 of the pole changer will move, respectively, into engagement with the contacts 4 and 5, so that the current will flow in the opposite directions through the magnet G and 35 change its polarity. The switch blade 21 will thus be repelled, and a second blade 29 will be attracted, so that this switch will be closed and a circuit will be established from the battery 22, through the conductor 23, through the operating mechanism of the signal I, through a conductor 30, through a switch 31, closed concurrently with the switch 29, through the conductor 32, through the switch 29, through the conductor 33, back 40 to the battery, when a manually operable switch 34, in the latter conductor, has been closed. Thus, when the switch points S of the railway are in either of their operative 45 positions, the proper signal will be cleared. 50 However, during the shifting of the switch points S from one position to the other, the relay G will be short-circuited. This is due to the fact that the switch 17 is closed on the withdrawing of the plunger lock D from 55 its engagement with the lock rod C. There-

fore, even if the switch 14 remains closed for an instant after the plunger lock is withdrawn from the lock rod, the magnet G will be short-circuited, and, therefore, will not be capable of operating either of the signal 70 circuits. From this, it will be obvious that the magnet G is not only short-circuited when the switch points S are in actual motion from one position to the other, but also when they are located in either of said positions and the plunger lock is not in engagement with the lock rod. 75

The embodiment of the pole changer illustrated in Figs. 2, 3, 6, 7, 8 and 9 includes a casing 35, to which a cover 36 is hinged. A 80 square shaft 37 is rotatably mounted in this casing, and one end of the shaft extends through one side of the same. To this extended end of the shaft, a crank arm 38 is secured, which crank arm is connected, at 85 39, to the rod E, which has previously been described, and which is connected to the railway switch points.

Located within the casing 35 and extending transversely thereof and parallel to the 90 shaft 37 is a plate 40, of insulating material. A pair of spring contacts, which correspond to the contacts 3 and 4 in Fig. 1, and are represented by the same characters in Figs. 2 and 3, are supported by the insulating plate 95 40 and are provided with binding posts 41 and 42, while a second pair of spring contacts, which correspond to the contacts 4 and 5 in Fig. 1, and are represented by the numerals 4' and 5, are also supported by this 100 plate 40 and are provided with binding posts 43. A pair of movable resilient switch blades, corresponding to the switch blades 1 and 2 of Fig. 1 and indicated by the same characters in Figs. 2 and 3, are supported 105 by the plate 40, are provided with binding posts 44 and are adapted to move into engagement with the contacts 3 and 4, or the contacts 4' and 5. Thus, the conductors 6 and 7 may, in actual practice, be connected 110 to the binding posts 41 and 42 of the contacts 3 and 4, and the conductor 7 may also be connected to the binding post 43 of the contact 4', while the conductor 8 may be connected to the binding post 43 of the contact 115 5. Thus, when the switch blades 1 and 2 are shifted into engagement with the contacts 3 and 4', current will flow through the magnet G in one direction, and when these switch blades are shifted into engagement 120 with the contacts 4 and 5, the direction of current will be reversed. It is, of course, obvious that instead of having a common return wire from a pair of the contacts, two separate wires may be used, in a manner 125 which will be obvious.

The upper ends of the switch blades 1 and 2 are loosely engaged with an insulating plate 45, which is carried by a pair of rock arms 46 and 47, the latter being pivoted at 130

48 to the casing 35, so that upon the movement of the rock arms, the switch blades 1 and 2 will be shifted into engagement with either pair of contacts.

5 In order that these rock arms may be properly moved upon the movement of the switch points S of the rails, and the consequent rotation of the shaft 37, I have provided a pair of cams 49 and 50, mounted on 10 the shaft 37. The cam 49 is provided with a cam slot 51 in which a roller 52, carried by the arm 46, operates, while the cam 50 is provided with a cam slot 53, in which a similar roller 54, carried by the arm 47, 15 operates. These cams are so arranged on the shaft, that is to say, one in advance of the other, that the cam 49 operates to move the rock arms 46 and 47, and, consequently, the switch blades 1 and 2, while the cam 50 20 is idle. The cam 50 operates to move these switch blades, subsequently, while the cam 49 is idle. For instance, assuming that the switch blades 1 and 2 are in engagement with the spring contacts 4 and 5 and the 25 switch points S of the railway are shifted. The cam 49 will move the switch blades 1 and 2 out of engagement with the contacts 4 and 5 into a neutral position between these contacts and the contacts 3 and 4', at 30 which time it will be rendered inoperative. The further movement of the switch points S will cause the cam 50 to come into operation and move the switch blades 1 and 2 into engagement with the contacts 3 and 4'. 35 It is, of course, desirable to have the cams adjustable on the shaft 37, and in order that such adjustment may be brought about, I have mounted on the shaft at each end thereof, an arm 55 which rotates with the shaft 40 and is provided at its upper end with a vertically elongated opening 56, and at the end through which the shaft passes with a hub 57. On these hubs, the cams previously referred to are rotatably mounted. Extending 45 through the opening 56, in each of the arms 55, is a stud 58 which extends through an enlarged opening 59 in the adjacent cam and is provided with a threaded opening in one of its ends and with a nut 60 at its 50 other end. Extending through the threaded opening in each stud is a screw 61, which is mounted in ears 62 on the adjacent cam and is held in place by a nut 63. By adjusting these screws 61, the cams may be rotated 55 with relation to the arms 55, independently of each other, and, consequently, the relative positions of the cams may be varied.

Formed integral with the casing 35 is a casing 64 having a cover 65 hinged thereon, 60 at 66, and secured thereto by means of swinging bolts 67. This casing 64 is provided with an extension 68 having a channel 69 therein and having a cover 70 which is held in place by suitable bolts 71. An 65 opening is provided above the channel 69

and is closed normally by a cover 72, which is hinged at 73. Through this channel 69 the lock rod extends. The plunger lock D, which preferably is rectangular in cross-section, is slidable in the extension 68 of the 70 casing 64 and is adapted to pass through the notches 74 in the lock rod to lock the latter. Extending transversely of the casing 64 is a plate 75 of insulating material, on which a pair of spaced spring contacts, corresponding 75 to the contacts 11 and 18 which are illustrated in Fig. 1 and are here indicated by the same characters, are located. The ends of these contacts 11 and 18 are spaced from each other, and associated with the same are 80 switch blades 14 and 17, corresponding to the blades illustrated in Fig. 1. The contacts 11 and 18 are provided with binding posts 76 and 77, while the switch blade is provided with a binding post 78. In actual practice, 85 the conductor 10 is attached to the binding post 76, the conductor 19 is attached to the binding post 77, while the conductors 13 and 15 are attached to the binding posts of the switch blades 14 and 17, respectively, so that 90 when the switch blade 14 is moved into engagement with the contact 11, the circuit will be closed through the magnet G, and when the switch blade 17 is moved into engagement with the contact 18, the magnet 95 will be short-circuited. In order that the movement of the switch blades 14 and 17 may be produced and properly controlled, I have pivoted a rock arm 79 to the base of the switch casing 64, at 80, and have attached 100 the upper ends of the switch blades, loosely, to a block of insulating material 81 carried by the rock arm. An adjustable link 82 is pivoted midway between the ends of this rock arm 79 and to a vertically movable 105 slide 83 which operates in suitable guide-ways formed in the wall of the casing 64, as illustrated in Fig. 4 of the drawings. Upon the upward movement of this slide 83, the rock arm 79 will be moved in one direction, 110 so that the switch blade 14 will be moved into engagement with the contact 11, and will thus complete the circuit above referred to. When, however, the opposite vertical movement of the slide 83 takes place, the switch blade 14 will be moved out of engagement with the contact 11, while the switch blade 17 will be moved into engagement with the contact 18, thus short-circuiting the magnet G. The movements of the 115 slide 83, and, consequently, the opening and closing of the above-mentioned circuits, are positively produced and controlled by the plunger lock in its movements, which lock is positively thrust into its locking position 120 or into its inoperative position. The end of this plunger lock extends through the wall of the casing 64 and is provided, on its upper surface, with a cam face 84, and on its under surface with a cam face 85. Mounted 125

130

on the slide 83 is a pair of rollers 86 and 87, between which the plunger lock D extends, so that the upper member 86 of the pair will ride upon the upper surface of the plunger lock, and the lower member 87 of the pair will ride upon the lower surface thereof. Because of the fact that the slide 83 is vertically movable, the rollers 86 and 87 will move over the cam faces 84 and 85, respectively, during the reciprocating movement of the plunger lock, whereby a positive reciprocating movement will be imparted to said slide 83. Thus, when the plunger lock is thrust into its locking position, it will raise the slide 83 to close the circuit, as above indicated, and when it is retracted, the slide will move to its lower position and be effective to break the previously closed circuit and close the switch to short-circuit the magnet G.

In the form of mechanism above described, additional switch blades and contacts are illustrated, which may be used for the closing of any circuits, signal circuits, for instance, as are desired.

In Figs. 10 and 11 of the drawings, the lock rod, the extension 68' with its cover 70' and the auxiliary cover 72', together with the plunger lock are illustrated. In this form of the device, a casing 88 is arranged adjacent to the extension 68' and may, of course, as illustrated in the drawings, be formed integral with the same or separate, if desired. The plunger lock D extends 35 into the casing 88, in a manner similar to that in which it extends into the before-described casing 64. This casing 88 is provided with a cover 89 which is hinged at 90, and mounted within the casing 88 is a bar 91 having its upper and lower faces covered with insulating material. Secured to the upper side of the bar 91, by means of a pair of binding posts 92 and 93, is a spring contact 94 which corresponds to the contact 18 in the form illustrated in Figs. 4 and 5. The binding post 92 is insulated by a suitable washer 95 of insulating material from the contact 94. This binding post 92 is electrically connected to a switch blade 96 which corresponds to the switch blade 17, in the form illustrated in Figs. 4 and 5. A second spring contact 97 is secured to the under face of the bar 91 by binding posts 98 and 99, the former of which is insulated from the contact by a suitable washer 100 of insulating material. This contact 97 corresponds to the contact 11 in the form illustrated in Figs. 4 and 5. The binding post 98 is electrically connected to the switch blade 101. Thus, when this switch blade 96 is shifted to engage the contact 94, the magnet G will be short-circuited, but when the blade 101 is shifted to engage the contact 97, the magnet will be energized.

65 In order that the movement of the switch

blades 96 and 101 may be produced, I have provided a vertically movable slide 102, which is normally held in its uppermost position by a pair of springs 103. This slide carries, adjacent to its upper end, a block 70 104 of insulating material with which one end of the switch blade 96 is loosely engaged. The movement of this slide will operate the switch blade 96 to close the proper circuit. 75

The movement of this slide 101 and the consequent opening and closing of the circuits described, is controlled by the plunger lock D, and to produce this control of the slide, I have provided a roller 105 which is 80 carried by the slide 102 and have formed a cam face 106 on the end of the plunger lock D, so that upon the inward movement of the latter, that is to say, upon its locking movement, the riding of the cam face 106 over 85 the roller 105 will positively move the latter, together with the slide on which it is mounted, downwardly, and will, consequently, complete the circuit with the contact 97. When, however, the plunger lock 90 is withdrawn, the springs 103 will move the slide upwardly, opening the previously closed circuit and closing the circuit with the contact 94.

In the form illustrated in Figs. 10 and 11, 95 a plurality of switch blades and contacts are shown which may be used to close any desired signal or similar circuits.

What I claim is:—

1. The combination with a railway switch 100 and its operating means, of means for controlling a plurality of electric circuits including means for closing the circuits, a selector operated by the switch for automatically controlling said closing means, 105 and manually operated means for rendering said closing means inoperative during the movements of the switch.

2. The combination with a railway switch 110 and its operating means, of means for controlling a plurality of traffic signal circuits including means for closing the circuits, a selector operated by the switch for automatically controlling said closing means, and manually operated means for rendering said 115 closing means inoperative during the movements of the switch.

3. The combination with a railway switch and its operating means, of means for controlling a plurality of electric circuits in- 120 cluding means for closing said circuits, means, operated by the switch, for rendering the closing means in condition to be operated, manually operated means for locking the switch, and means associated with said 125 locking means for rendering the closing means inoperative except when the switch is locked.

4. The combination with a railway switch and its operating means, of means for con- 130

- trolling a plurality of traffic signal circuits including means for closing said circuits, means, operated by the switch, for rendering the closing means in condition to be operated, manually operated means for locking the switch, and means associated with said locking means for rendering the closing means inoperative except when the switch is locked.
- 10 5. The combination with a railway switch and its operating means, of means for controlling a plurality of traffic signal circuits including means for closing said circuits, means, operated by the switch, for rendering the closing means in condition to be operated, manually operated means for locking the switch, and means operated by the locking means for rendering the closing means inoperative except when the switch is locked.
- 15 6. The combination with a circuit controller, of means for actuating the same which embody a pair of oscillatory cams and a screw-adjustment for adjusting the cams with relation to each other in accordance with the throw of the switch points.
- 20 7. The combination with a circuit controller which embodies a plurality of pairs of spaced contacts, and a plurality of movable blades each arranged to engage either pair of contacts, of means for actuating the blades which includes a pair of relatively adjustable oscillatory cams, said adjustment being accomplished by a tangentially disposed screw, and common means for oscillating said cams.
- 25 8. The combination with a pair of railway switch rails, of a circuit controller, a rock shaft, a pair of cams on said shaft each effective for giving separate movement to the circuit controller at different times, a tangentially disposed screw for adjusting one cam relatively to the other, and connecting means from the switch for actuating the rock shaft.
- 30 9. The combination with a railway switch and its operating means, of means for controlling a plurality of traffic signal circuits including a polarized relay, a pole changer operated by the switch, and means for short circuiting the relay except when the switch is in locked position.
- 35 10. The combination with a railway switch and its operating means, of means for controlling a plurality of traffic signal circuits including a polarized relay for closing the circuits, a pole changer in circuit with the relay comprising a plurality of contacts, a plurality of movable switch blades, a pair of cams for giving successive movements to said switch blades, and an operating connection between the cams and the railway switch.
- 40 11. The combination with a railway switch and its operating means, of means for controlling a plurality of traffic signal circuits including a polarized relay for closing the circuits, a pole changer in circuit with the relay comprising a plurality of contacts, a plurality of movable switch blades, a pair of cams for giving successive movements to said switch blades, an operating connection between the cams and the railway switch, and means for short circuiting the relay during the movement of the railway switch.
- 45 12. The combination with a railway switch and its operating mechanism, of manually operated means for locking the switch in its operative positions, a polarized relay for closing a traffic signal circuit, a pole changer for said relay, and means for short circuiting the relay when the switch is unlocked.
- 50 13. The combination with a railway switch and its operating mechanism, of manually operated means for locking the switch in its operative positions, a polarized relay for closing a traffic signal circuit, a pole changer for said relay, and means, operated by the switch locking means, for short circuiting the relay when the switch is unlocked.
- 55 14. The combination with a railway switch and its operating mechanism, of means for locking the switch in its operative positions including a lock rod connected to the switch, a manually operated plunger lock adapted to engage the lock rod, a relay for closing a traffic signal circuit, means for energizing said relay, and means, operated by the plunger lock, for short circuiting the relay when the plunger lock is inoperative to lock the switch.
- 60 15. The combination with a railway switch and its operating mechanism, of a polarized relay, a pole changer for the relay operated by the switch, said pole changer comprising a plurality of oppositely arranged contacts, a switch blade arranged between the same, a pair of cams arranged to impart sequential movements to said switch blade, means for adjusting the cams to vary their relation to each other, and means connected to the railway switch to actuate the cams.
- 65 16. The combination with a railway switch and its operating mechanism, of a lock rod connected to the switch, a polarized traffic-signal controlling relay, a pole changer in circuit with said relay and operated by the switch, a plunger lock adapted to engage the lock rod to maintain the switch in its operative position, means controlled by the plunger lock for completing the circuit through the relay when the lock is in its operative position and means controlled by the lock for short circuiting the relay when the lock is in its operative position.
- 70 17. The combination with a railway signal apparatus which includes a signal control circuit, of means for opening and closing a pair of breaks in said circuit, which means
- 130

embodies a plunger lock controller effective for controlling one of said breaks and a switch selective circuit controller connected to the switch points effective to control the other of said breaks, the closing of both said breaks being essential to clearing of a signal.

Signed at New York, in the county of New York, and State of New York, A. D. 1917.
